UNITED STATES PATENT OFFICE.

AUGUST J. MOTTLAU, OF PITTSBURGH, PENNSYLVANIA, ASSIGNOR TO WESTINGHOUSE ELECTRIC & MANUFACTURING COMPANY, A CORPORATION OF PENNSYLVANIA.

THERMAL RELAY.

Application filed October 9, 1926. Serial No. 140,568.

My invention relates to protective relays for electric translating devices and particularly to thermally actuatable relays.

An object of my invention is to provide an electric control switch that shall be operable by a plurality of current-conducting bimetallic elements that are energized in accordance with the current flowing in a circuit to be controlled.

10 Another object of my invention is to provide a plurality of integral, parallel, spaced bimetallic elements that shall be operable as a unit in response to a predetermined current condition therein to actuate a control circuit.

15 Another object of my invention is to provide a thermal relay that shall be operable over a wide range of current conditions in a circuit to be protected.

Another object of my invention is to provide a thermal relay that shall automatically return to its operative position after a relatively short period of time after being actuated to an inoperative position.

In practicing my invention, I provide a plurality of slotted bimetallic elements that are so disposed in parallel planes, one above another that they combine to produce a unified motion when they are thermally energized from an electric circuit. The elements are electrically connected together in series-circuit relation. In the preferred embodiment of my invention, I propose to make the bimetallic elements from a single sheet of material.

35 Means are provided for holding a central portion of the bimetallic elements in a relatively fixed position with respect to the ends thereof. A control switch is disposed in operative relation to the bimetallic elements and is actuated thereby through a plurality of intersecting links that are operated with a scissorlike motion. The control switch may be moved away from, or towards, the actuating mechanism in accordance with 40 the condition of the bimetallic elements that is selected as desirable.

In the accompanying drawings, Fig. 1 is a plan view of the device embodying my invention.

50 Fig. 2 is a view, partially in section and

partially in side elevation, of the device illustrated in Fig. 1, taken on the line II-II thereof.

Fig. 3 is a top plan view of a pair of lever members embodied in my invention, 55

Fig. 4 is a view, similar to Fig. 2, but showing the relay in an actuated position.

Fig. 5 is a top plan view of a detail embodied in the device illustrated in Figs. 1, 2 and 3, and 60

Fig. 6 is an end view of the detail illustrated in Fig. 5.

In the drawings, a thermally actuatable relay 11 comprises a base member 12, a thermo-responsive means 13, a switch 14 and 65 an actuating mechanism 15. The thermo-responsive means 13 comprises a plurality of parallel, spaced-apart bimetallic members 16, 17 and 18. Each of the bimetallic elements 16, 17 and 18 has a longitudinally- 70 extending slot or aperture 19 (see Fig. 5) and they are electrically connected from opposite sides by narrow integral metallic connecting portions 21 and 22. The members 16, 17 and 18 and the connecting portions 21 75 and 22 are separated from each other by suitable insulating strips 23.

The thermo-responsive means 13 is supported by a block of insulating material 24 that is suitably secured to the base member 12 by bolts 25 and 26. The ends of the bimetallic portion 18 of the thermo-responsive means 13 have mounted thereon a plurality of angle pieces 27 that are secured thereto by rivets 28. The pieces 27 are provided with aligned apertures 29 to receive 80 a pin 31.

The actuating mechanism 15 comprises a pair of levers 32 and 33 that are pivotally secured in operative engagement with the members 27 by the pins 31. The lever 33 (see Fig. 3) comprises two alined portions 34 and 35 that are joined together in operative relation by a pair of metal supporting members 36 secured to the sides thereof between which an aperture 37 is formed. The members 36 are secured to the members 34 and 35 by rivets 38. The member 32 extends through the aperture 37 in such manner that the members 32 and 33 intersect and 95 100

are, therefore, disposed in substantially the same plane.

An insulating block 39 is supported by the bolts 25 and 26 in a predetermined position by nuts 41 and 42.

The switch 14 is secured to the block 39 by a pair of bolts 43 and 44 and comprises a resilient metal frame 45 having a pair of apertures 46 and 47 punched therein to provide a bridging member 48 which extends longitudinally of the frame 45. The bolts 43 and 44 extend through the sides of the frame 45 to secure the switch to the block 39. The frame 45 is provided with deformed end portions 49 of such dimensions and shape that the apertures 46 and 47 are substantially shorter than the bridging member 48. The bridging member 48 comprises a pair of upwardly curved end portions 51 and an intermediate downwardly deflected portion 52. A contact member 53 is mounted on the bridging member 48 and is adapted to engage a contact member 54 that is mounted on the insulating block 39.

The contact member 54 is maintained in position on the insulating block 39 by a bolt 55 which serves as one terminal for the control switch 14. A bolt 56, which forms a second terminal for the switch 14, extends through the block 39 and registers with one side of the frame 45. The ends of the switch 14 are provided with spaced-apart depending members 57 of L-shape, which members have aligned apertures 58, through which pins 59 extend. The members 57 are secured to the frame 45 by rivets 60.

The members 32 and 33 are provided with notched end portions 62 which extend between the depending members 57 to rest on the pins 59.

When such bending force is applied to the members 57 of the switch 14 that the right and left-hand ends thereof tend to rotate in counter-clockwise and clockwise directions, respectively, the bridging member 48 is stressed until the portion 52 thereof reaches a state of unstable equilibrium. If the bending force is increased still further, the intermediate portion 52 will be caused to deflect to a state of stable equilibrium, with a sudden snap-motion, thereby disengaging the contact member 53 from the contact member 54. The portion 52 will remain in its deflected position so long as the bending force is applied, but, in the event it is removed, the portion 52 will return to its normal position, as illustrated in Fig. 2, with a snap motion.

The bending force referred to above is applied by means of the bimetallic means 13 and the intersecting members 32 and 33. When the bimetallic means 13 is heated by an electric current flowing therein, the free ends thereof curve upwardly. (See Fig. 4).

The switch 14 may be moved vertically

towards or away from the bimetallic means 13 by turning the nut 41, which operatively engages the block 39 and the bolt 25, in the proper direction. As the switch is moved upwardly, the notched end portions 62 of the members 32 and 33 slide freely on the pins 59.

When the bimetallic members 16, 17 and 18 are connected in a heavy-current circuit by means of a pair of terminal members 63 and 64, the heating produced therein by the resistance losses incidental to current traversing the conductors causes the free ends thereof to curve upwardly, substantially as illustrated in Fig. 4 of the drawings. As the elements curve upwardly, the members 32 and 33 are caused to move upwardly and laterally, but in opposite directions, until the notched portions 62 thereof register with the pins 59, whereby bending moments are applied to the members 57. When the bimetallic members 16, 17 and 18 have curved upwardly until the members 57 and 58 of the switch 14 have been bent outwardly and upwardly, as indicated in Fig. 4 of the drawings, contact member 53 will have become disengaged from the contact member 54. I have found, by experiment, that the switch functions very satisfactorily when actuated by the thermal means 13 and the intersecting members 32 and 33 associated therewith, in the manner hereinbefore described.

The switch 14, as illustrated in the drawings, specifically constitutes no part of my invention, as it is described and claimed in my Patent No. 1,668,974 issued May 8, 1928 and assigned to the Westinghouse Electric and Manufacturing Company.

The terminal members 55 and 56 of the switch 14 may be assumed to be connected in circuit with the holding coil of a circuit interrupter, a device which controls a heavy-current circuit in which the bimetallic means 13 may be connected. When the current traversing the bimetallic means 13 has reached a predetermined value, the expansion thereof, as illustrated in Fig. 4 of the drawings, will cause disengagement of the contact members 53 and 54 to de-energize the control circuit, with the consequent de-energization of the heavy-current circuit. When the bimetallic means 13 has cooled sufficiently to assume the position illustrated in Fig. 2 of the drawings, the switch 14 will automatically reclose itself and assume the position illustrated in Fig. 2 of the drawings. The heavy-current circuit will then be ready to be energized for further service.

If it is desirable that a relatively large current shall traverse the bimetallic means 13 before the switch 14 is actuated to the position illustrated in Fig. 4, the latter is moved upwardly by the adjusting nut member 41. It is, therefore, evident that the bimetallic members 16, 17 and 18 must be

heated to a higher temperature before the notched portion of the members 32 and 33 will engage the pins 59 of the switch 14.

If it is desirable that a relatively small current shall be effective to actuate the control switch 14, the adjusting screw 41 is turned until the switch 14 has been lowered to the desired position. It is, therefore, evident that the bimetallic means need not be heated to so high a temperature as referred to above to actuate the switch 14.

The bimetallic means 13, as illustrated in the drawings, may be made a single flat sheet of bimetallic material by punching the apertures 19 therein and by cutting away material from the ends longitudinally thereof so that the members 16, 17 and 18 formed thereby are joined by the intervening strips 21 and 22, and by so folding the flat bimetallic sheet, after the necessary punching operation, that the corresponding metals of the sheet extend in the same direction, as illustrated particularly in Fig. 6 of the drawings, the heating of the elements will result in a deflection thereof in the same direction. The ends of the bimetallic members 16, 17 and 18 may be maintained in spaced relation by suitable electric insulating spacing members 66.

Since the bimetallic elements 16, 17 and 18 are traversed by electric current, they respond very quickly to changes in current and particularly when a sudden abnormal value of current flows therethrough. This responsive feature would not be available (when the current changes suddenly to an abnormally large value) if the bimetallic elements were enclosed by an independent resistor member, because the air between the resistor and the elements would act as a thermal insulator. It follows, also, that the elements 16, 17 and 18 will cool quickly because the surrounding air may circulate freely between them, thereby affording a quick reset of the switch 14 after it has been actuated to the position illustrated in Fig. 4.

By my invention, I provide a thermal relay that is simple in construction, that has relatively few parts, and that is positive in operation. In general, I provide a bimetallic thermally-responsive means that is adapted to be heated by an electric current traversing it. The bimetallic means actuates a control switch by means of a simple operating mechanism when a predetermined value of current has traversed it for a predetermined length of time. The control switch may be moved away from, or towards, the bimetallic elements to thus provide a relatively wide range of current conditions to which the current traversed means may be subjected before actuating the control switch.

Various modifications may be made in the device embodying my invention without departing from the spirit and scope thereof.

I desire, therefore, that only such limitations shall be placed thereon as are imposed by the prior art and the appended claims.

I claim as my invention:

1. The combination with a control switch comprising an apertured resilient frame and a bridging member extending across the aperture, and thermo-responsive means, of a plurality of intersecting members operatively engaging the frame and said thermo-responsive means for actuating said frame to cause deflection of said bridging member upon movement of the thermo-responsive means.

2. In a switch structure, a quick-break control switch, an elongated thermo-responsive bimetallic strip, and a plurality of intersecting members operatively engaging said bimetallic strip and control switch for actuating said switch when the bimetallic strip has reached a predetermined thermal condition.

3. In a switch structure, a quick-break control switch, an elongated thermo-responsive bimetallic strip, and a plurality of independent members operatively engaging said bimetallic strip and control switch for actuating said switch when the bimetallic strip has attained a predetermined thermal condition.

4. In a switch structure, a control switch having contact members therefor normally biased into an engaged position, a plurality of serially connected spaced-apart bimetallic strips, and a pair of independent intersecting members disposed in operative engagement with the ends of said bimetallic strips and said switch for actuating the contact members to a disengaged position when the bimetallic members have reached a predetermined thermal condition.

5. In a thermal relay, the combination with a circuit controlling device comprising a metal plate having an aperture therein and a bridging member extending across the aperture, of a bimetallic unit and a pair of independent intersecting members disposed in parallel planes, actuated by the bimetallic unit to apply deflecting thrusts to the ends of the plate for actuating the bridging member.

6. In a thermal relay, the combination with a switch, and an actuating mechanism therefor, of thermally responsive means for actuating said mechanism, comprising a plurality of spaced-apart apertured bimetallic members disposed one above the other and adapted to deflect in the same direction, said members being held fixed at the central portions thereof and being integrally connected from opposite sides substantially at said central portions.

7. The combination with apertured elongated bimetallic members, and a pair of independent intersecting members, each of

said members having one end thereof pivotally secured to opposite ends of said bimetallic members, of a switch member supported in operative engagement with the 5 other ends of said intersecting members for operating the switch when a predetermined thermal condition exists in the bimetallic member.

8. The combination with an apertured 10 elongated bimetallic member, a pair of independent intersecting members, each of said members having one end thereof pivotally mounted at opposite ends of said bi-

metallic member, a switch member supported in operative engagement with the other 15 ends of said intersecting members, of means for moving said switch away from or towards said intersecting members in accordance with a predetermined thermal condition at which said bimetallic member shall 20 be effective to operate the switch.

In testimony whereof, I have hereunto subscribed my name this 2nd day of October, 1926.

AUGUST J. MOTTLAU.
